[57] CLAIM

We claim the ornamental design of a paint sprayer fan shroud, as shown and described.

DESCRIPTION

FIG. 1 is an isometric view, taken from the front, of a paint sprayer having a fan shroud embodying the ornamental design of the present invention;

FIG. 2 is an isometric view, taken from the rear, of the paint sprayer of FIG. 1;

FIG. 3 is a side view of the paint sprayer of FIG. 1;

FIG. 4 is an opposite side view of the paint sprayer of FIG. 1;

FIG. 5 is a front view of the paint sprayer of FIG. 1;

FIG. 6 is a rear view of the paint sprayer of FIG. 1;

FIG. 7 is a top view of the paint sprayer of FIG. 1;

FIG. 8 is a bottom view of the paint sprayer of FIG. 1; and, FIG. 9 is a view similar to FIG. 1 showing a paint bucket mounted on the paint sprayer.

The broken line showings in FIG. 1-9 are for illustrative purposes only and form no part of the claimed design.
